UNITED STATES PATENT OFFICE.

JAY REED, OF BUTLER, MISSOURI.

HARNESS-STRAP ATTACHMENT.

SPECIFICATION forming part of Letters Patent No. 509,449, dated November 28, 1893.

Application filed March 17, 1893. Serial No. 466,427. (No model.)

To all whom it may concern:

Be it known that I, JAY REED, a citizen of the United States, residing at Butler, in the county of Bates and State of Missouri, have 5 invented certain new and useful Improvements in Harness-Strap Attachments; and I do hereby declare that the following is a full, clear, and exact description of the same, reference being had to the annexed drawings, 10 making a part of this specification, and to the letters of reference marked thereon.

The present invention has for its object to provide a strap with buckle and loop attachments which is adapted for use in all classes 15 of harness and especially the hames of horse-collars, and consists in the details of construction substantially as shown in the drawings and hereinafter described and claimed.

Figure 1 of the drawings represents a longitudinal section of a harness strap provided 20 with the attachments which constitute my invention. Fig. 2 represents a detail view in perspective of the plate with loops, one of which is shown as detached; Fig. 3 a similar 25 view of the bearing plate with loop and T headed button; Fig. 4 a perspective view of the bearing plate, showing a modification thereof.

In the accompanying drawings A represents 30 a harness strap adapted for attachment to the ends of a hame as shown in dotted lines Fig. 1, although such strap may be used for other purposes where it would be found of value. To one end of the strap is connected a suitable buckle B and between the folds of the 35 strap is located a brace-plate C connected thereto by a rivet a which passes through the folds of the strap and through a hole b in the plate. The brace-plate is constructed of a 40 rectangular piece of sheet metal bent upon itself to form eyes for the attachment thereto of one or more loops, as shown in Fig. 2. The hole in the plate is somewhat larger in diameter than the diameter of the rivet to admit 45 of the use of the common riveting machine in fastening it to the strap. The brace-plate C which braces and strengthens the end of the strap, has one or more loops D connected thereto in any suitable manner. These loops 50 may be constructed of wire and afterward

connected to the ends of the plate by bending the sheet metal thereof around the split portion of the loops and the metal pressed tightly against it to prevent the split from spreading. If preferred the plate may be cast or otherwise 55 formed integral with the loops so that they will be rigid, and one or more loops may be used as found desirable when applied to small or large collars.

A suitable hooked bearing plate E is provided 60 to take the wear off the leather strap and at the same time to form a brace therefor, and is preferably constructed from a single thickness of sheet metal and may be used with or without the loop F as found desirable, 65 the loop being connected to the plate as shown in Fig. 3, or formed rigid with the plate by casting or otherwise. The hooked bearing plate E may be permanently attached to the strap by riveting or otherwise and at any desirable 70 distance from the buckle, or may be adjustable thereon as shown, so as to increase or diminish the distance between it and the buckle, as circumstances may require. There may be many ways in which the bearing 75 plate can be rendered adjustable upon the strap, and in the present instance I have shown one which I think might be used to advantage, and consists of a button c having a T-shaped head. This button is pivotally connected 80 to the plate E so as to turn on its axis to bring the head crosswise of one of the holes d, thus holding the plate to the strap, and when it is desired to disconnect the plate with the strap, the button is turned so as to 85 bring the head lengthwise of the hole and enable it to pass through.

Having now fully described my invention, what I claim as new, and desire to secure by Letters Patent, is—

1. A hame-strap provided with a suitable buckle at one end, a brace-plate constructed of sheet metal bent upon itself to form eyes and located between the folds of the strap and connected thereto, one or more loops engaging 95 with the eyes of the brace plate, and a hooked bearing-plate connected to the strap, substantially as and for the purpose set forth.

2. A hame-strap provided with a suitable buckle at one end, a brace-plate located be- 100

tween the folds of the strap and connected thereto and having one or more loops, and a hooked bearing plate adjustably connected to the strap to increase or decrease the distance between it and the buckle or brace-plate, substantially as and for the purpose described.

5 In testimony that I claim the above I have

hereunto subscribed my name in the presence of two witnesses.

JAY REED.
